UNITED STATES PATENT OFFICE.

FRANK KUHN AND JAY A. HAND, OF DETROIT, MICHIGAN, ASSIGNORS TO AMERICAN ELECTRICAL HEATER COMPANY, OF DETROIT, MICHIGAN, A CORPORATION OF MICHIGAN.

FOOT-WARMER.

1,288,045.

Specification of Letters Patent. Patented Dec. 17, 1918.

Application filed March 14, 1918. Serial No. 222,286.

To all whom it may concern:

Be it known that we, FRANK KUHN and JAY A. HAND, both citizens of the United States of America, residing at Detroit, in the county of Wayne and State of Michigan, have invented certain new and useful Improvements in Foot-Warmers, of which the following is a specification, reference being had therein to the accompanying drawings.

This invention relates to a foot warmer and is designed for use by aviators and motorists or others following vocations requiring exposures to extremes of cold.

It is the object of the invention to associate heating elements with a pair of shoes or other footwear preferably in a detachable relation so that the feet of the wearer will be protected against the danger and discomfort resulting from exposure to cold.

In the accompanying drawings:

Figure 1 is a top view of a heating element having the nature of an insole detachably insertible in an ordinary shoe;

Fig. 2 is a perspective view of the heel portion of a shoe equipped with said insole, the electrical connections to the resistor being shown;

Fig. 3 is a detail sectional view of one of the electrical connections, the section being taken on line 3—3 of Fig. 2;

Fig. 4 is a view similar to Fig. 1 but showing the insole provided with a modified form of contact;

Fig. 5 is a perspective view of the heel portion of a shoe provided with contacts engageable by those carried by said modified insole;

Fig. 6 is a sectional view of the modified construction, the section being taken on line 6—6 of Fig. 5.

Referring now in detail to the invention as disclosed in Figs. 1, 2 and 3, the reference character 1 designates a shoe and 2 a heating element insertible in said shoe and having the nature of an insole comprising two flexible insulatory plates, the edges of which are stitched together as indicated at 3 and between which a resistor 4 is arranged to trace a circuitous course, said resistor being preferably formed of a braided wire so that it may have the requisite flexibility.

At each side of the heel portion of the insole 2 the extremities of the resistor 4 are respectively connected to a pair of upwardly

projecting contacts 5 having the nature of 55 metallic strips, said strips lying closely adjacent the inner face of the upper of the shoe when the insole is in place. The upper extremities of the contacts 5 are adapted to be detachably engaged by S-shaped 60 connectors 6 formed of spring-metal and adapted to clamp upon the upper edge portions of the shoe, as seen in Fig. 2. Each of said connectors has a portion adapted to extend within the engaged shoe and is formed 65 at its lower extremity with a sleeve 7 to receive the corresponding strip 5. Exteriorly of the engaged shoe each connector 6 is provided with a portion slotted vertically, as indicated at 8, said slot being adapted to receive the neck portion of a stud 9 projecting from the terminal sleeve 10 of a conductor 11. The relative proportioning of the studs 9 and members 6 is such that the slotted portion of either member 6 will be 75 sprung out from the central portion thereof by the head of the engaging stud so that there will be resistance to displacement of the stud from said connector. The central portion of the connector is concaved, as indicated at 12, for engagement with said stud and when said engagement is established the member 10 may be swiveled about the axis of the stud to assume any desired angle without disturbing the electrical connection. 80 Such a connection is highly desirable where the feet of the person using the described device must operate one or more foot pedals, and consequently provision for play is necessary at the point of connection of the conductors to the shoe.

In the modification of Figs. 4 to 6 the resistor embedded in the detachable insole is provided with terminal contacts 13 of disk shape upon the under face of said insole, 95 said contacts engaging the heads of screws 14 in the heel portion of the shoe when the insole is in place. The screws 14 respectively engage contact plates 15 which are embedded in the heel of the shoe at each side 100 thereof, projecting laterally sufficiently to engage any suitable fixed contacts (not shown).

It will be observed that in either form of the invention the electrical conductors may 105 be very quickly attached or detached from the heating element; and furthermore that the heating element may, if desired, be

readily removed entirely from the shoe in case the latter is to be used for ordinary wear.

What we claim as our invention is:

- 5 1. A foot warmer comprising a shoe, a heating element carried thereby adjacent the sole thereof, a pair of terminals upwardly extending from said element, and a pair of spring clips yieldably engageable with the 40 shoe and providing for detachable engagement both with said terminals and lead wires.
- 10 2. A foot warmer comprising a shoe, a heating element carried thereby adjacent the sole thereof, a pair of terminals upwardly extending from said element, and a pair of members secured to the shoe having provision 45 interiorly thereof for engaging said terminals, and an exterior provision for engaging lead wires.
- 15 3. A foot warmer comprising a shoe, a heating element carried thereby adjacent the sole thereof, a pair of terminals upwardly extending from said element, and a pair of spring clips secured to the shoe having provision therewithin for quick detachable engagement with said terminals, and providing exteriorly of the shoe for engagement with lead wires.
- 20 4. A foot warmer comprising a shoe, a heating element carried thereby adjacent the sole thereof, a pair of terminals upwardly extending from said element, and a pair of members secured to the shoe detachably engaging said terminals and providing for 50 swivel connection with lead wires.
- 25 5. A foot warmer, comprising a shoe, a detachable insole for said shoe, a heating element carried by said insole, terminal contacts for said element carried by the insole, and a pair of connectors detachably engageable with the upper edge of the shoe and detachably engaged by said terminal contacts.
- 30 6. A foot warmer, comprising a shoe, a heating element carried thereby, terminal contacts for said element extending into proximity to the upper edge of the shoe, and a pair of connectors detachably engaged with said edge and detachably engaging said 55 terminal contacts.
- 35 7. A foot warmer, comprising a shoe, a heating element carried thereby adjacent the sole thereof, terminal contacts mounted upon the edges of the shoe, means for electrically connecting said contacts with said heating element, and means for swivelly connecting conductors with said contacts.
- 40 8. A foot warmer, comprising a shoe, a heating element carried thereby, a pair of S-shaped connectors, each of said connectors having one of its return-bent portions detachably engaging the upper edge of the shoe and having its other return-bent portion slotted to receive a conductor, the connectors being concaved opposite said slots to 55 form a swivel seat for said conductor.

In testimony whereof we affix our signatures.

FRANK KUHN.
JAY A. HAND.
